UNITED STATES PATENT OFFICE

153,249

DESIGN FOR A GRATER

George Albertson, Los Angeles, Calif.

Application April 1, 1947, Serial No. 138,091

Term of patent 3½ years

(Cl. D89—1)

To all whom it may concern:

Be it known, that I, George Albertson, a citizen of the United States, residing at Los Angeles, in the county of Los Angeles and State of California, have invented a new, original, and ornamental Design for Grater, of which the following is a specification, reference being had to the accompanying drawing, forming part thereof.

Figure 1 is a top plan view of a grater embodying my new design; and, Fig. 2 is a sectional view taken substantially upon the line 2—2 upon Fig. 1.

I claim:

The ornamental design for a grater, as shown.
GEORGE ALBERTSON.
